UNITED STATES PATENT OFFICE

161,081

SHUFFLEBOARD GAME TABLE

Roy Bazelon, Chicago, Ill.

Application March 2, 1949, Serial No. 1,164

Term of patent 3½ years

(Cl. D34—5)

To all whom it may concern:

Be it known that I, Roy Bazelon, a citizen of the United States, residing at Chicago, in the county of Cook and State of Illinois, have invented a new, original, and ornamental Design for Shuffleboard Game Table, of which the following is a specification, reference being had to the accompanying drawing, forming a part thereof.

In the drawing:

Fig. 1 is a perspective view of a shuffleboard game, showing my new design;

Fig. 2 is a top plan view thereof; and

Fig. 3 is a fragmentary longitudinal section taken along the line 3—3 of Fig. 2 looking in the direction of the arrows.

The dominant features of my new design are shown in solid lines in the drawing.

I claim:

The ornamental design for a shuffleboard game table, substantially as shown and described.

ROY BAZELON.
